CLAIM

The ornamental design for a portable light, as shown and described.

DESCRIPTION

FIG. 1 is a front/side elevational perspective view of the portable light;

FIG. 2 is a front view of the light;

FIG. 3 is a rear view of the light;

FIG. 4 is a first side view of the light;

FIG. 5 is a second side view of the light;

FIG. 6 is a top view of the light; and,

FIG. 7 is a bottom end view of the light.

The broken lines show portions of the article not claimed and form no part of the claim design.
